CHECKER ASSEMBLY FOR STOVE
CONSTRUCTIONErnest H. Koenig, Chicago, Ill., assignor to Freyn
Engineering Company, Chicago, Ill., a corpora-
tion of Maine

Application April 30, 1945, Serial No. 590,982

1 Claim. (Cl. 72—102)

1

The present invention relates to improvements in checker assembly for stove construction.

More particularly the present invention relates to improvements analogous to those disclosed and claimed in the application of Bruce E. Tau, Serial No. 535,271, filed May 12, 1944, for Stove construction.

In certain of its aspects the present invention may be said to cover a modification of the disclosure of said Tau application.

It is common practice to build a hot blast stove with an annular ring wall and to provide the interior of the stove with an assembly of checkers, which checkers provide a plurality of passageways for products of combustion for supplying heat to said checkers, which passageways in turn permit the flow of air to be heated by said checkers.

The checkers used in hot blast stoves are subjected to very high temperatures and should be supported in a substantial manner by the ring wall. Moreover, the checkers must be replaced at times, and it is important that the matter of replacement be made as simple as possible.

In certain arrangements of checkers the outer surface of the checker body is characterized by a very irregular serrated contour. It is difficult to build a satisfactory ring wall to join this contour satisfactorily. According to certain prior constructions the ring wall has been made up of a combination of key bricks and straight bricks laid radially to make a ring wall having a substantially smooth exterior contour and a substantially smooth interior contour. The space between the smooth interior contour and the irregular serrated contour of the checker body has been filled with irregularly shaped pieces of brick or the like and with clay. The construction just described has the disadvantage that the ring wall does not serve as a substantial support for the checker body, inasmuch as the intermediate filling between the interior surface of the ring wall and the exterior surface of the checker body is not strong. This type of construction lacks stability. This type of construction has the further disadvantage that if and when the checker body or portions thereof are removed for replacement, the filling material between the interior contour of the ring wall and the outer surface of the checker body falls off, inasmuch as it is not bonded to the ring wall and has very little inherent stability.

According to another prior construction, the ring wall is made up entirely of standard straight 55 bricks. Considerable difficulty has been experi-

2

enced in fitting these bricks to the irregular contour of the exterior of the checker body to provide the relatively intimate fit which is desired in order that the ring wall will serve to support the checker body for providing stability. In order to accomplish such fit it was necessary to cut a large number of bricks, usually by sawing. This involved a relatively great time for construction and relatively high construction cost. In some cases it was sought to obviate this high cost by omitting the relatively intimate fit between the ring wall and the exterior of the checker body and instead filling the space between the ring wall and the checker body in the manner generally described in previous paragraphs. This construction had the disadvantage above mentioned.

An object of the present invention is to provide a stove construction in which the interior of the ring wall and the exterior of the checker body engage along chords bounding the periphery of the checker body, the construction being such as to provide a maximum heat exchange area per unit of mass.

A further object is to provide an improved stove construction in which the periphery of the checker body is provided by a relatively small number of specially constructed checkers for providing a checker body having its exterior surface arranged along flat surfaces, the construction being such as to provide a relatively large heat exchange area per unit of mass.

A further object is to provide an improved stove construction of the kind immediately above referred to having the advantage that a ring wall may be fitted thereto without the expenditure of excessive time and/or labor.

A further object is to provide an improved edge checker which is useful in building a checker body the exterior wall of which is bounded by plane surfaces, the checker having the further advantage that the heat exchange area thereof is relatively large compared to the mass thereof.

A further object is to provide a hot blast stove construction which is simple and sturdy, which can be easily repaired, which meets the needs of commercial operation, and which provides a relatively high heat exchange area compared with its mass.

50 Further objects will appear as the description proceeds.

Referring to the drawings—

Figure 1 is a horizontal sectional view of a portion of a blast furnace stove embodying the principles of the present invention;

Figure 2 is a top plan view of one of the stand-

ard checkers utilized in the construction illustrated in Figure 1:

Figure 3 is a top plan view of a half checker such as utilized in forming the exterior wall of the checker body illustrated in Figure 1;

Figure 4 is a top plan view of another type of edge checker utilized in forming the exterior wall of the checker body illustrated in Figure 1;

Figure 5 is a sectional view taken along the plane indicated by the arrows 5-5 of Figure 4; and

Figure 6 is a fragmentary view on an enlarged scale of part of the construction illustrated in Figure 1, Figure 6 illustrating a corner construction.

Figure 1 represents in horizontal section a blast furnace stove, said stove having the ring wall 10 within which is the usual combustion chamber wall 11 providing the combustion chamber 12. Said ring wall 10 is made up of bricks and has a generally cylindrical exterior, though according to the present invention the exterior wall may be more or less serrated. Surrounding the ring wall 10 is the shell 13, and located between the exterior of ring wall 10 and the shell 13 is a body of insulating material indicated by the numeral 14. This insulating material may be merely of a filler character and need have no bond with the ring wall 10 or the shell 13. Accordingly, the bricks presented to the exterior of the ring wall 10 may be permitted to present a rather irregular surface and the cutting of the bricks need not be exact. As will appear as the description proceeds, the interior surface of the ring wall 10 will be a series of planes. Considering the perimeter of the inner surface of the ring wall 10 at any elevation, said perimeter is bounded by a plurality of chords.

The numerals 15-15 in Figure 2 indicate checkers of a known type, a large number of which are assembled within the ring wall 10 to constitute heat storing and heat transmitting bodies for storing up heat from products of combustion when the hot blast stove is on blast and for giving up heat to air passing through the stove when the stove is on blast.

The checkers 15-15 are of standard construction, the illustrated checker being the seven-hole type. The checker 15 chosen for illustration has a cross section in the shape of a regular hexagon, this meaning that the exterior flat surfaces 16-16 thereof lie in an equiangular, equilateral hexagon. Medially of the checker 15 is the center hole 17. Disposed in a circle about the center hole 17 are six other holes 18-18. The top side of the checker 15 is provided with a relatively shallow circular recess 19 communicating with the holes 17, 18, 18. The flat surfaces 16-16 of the checker 15 are joined by the arcuate portions 20-20. Extending transversely of the checker 15 is the arcuate groove 21 providing communication between the holes 17, 18 and the exterior of the checker. In the claims, checkers having a cross sectional contour of a regular polygon will be referred to as regular checkers. An assembly of standard or regular checkers such as those indicated by the numerals 15-15 will produce a serrated exterior wall of the checker body, and accordingly the present invention contemplates the use of supplementary checkers in cooperation with the standard or regular checkers 15-15 to produce an exterior wall for the checker body bounded by plane surfaces.

Figure 3 illustrates one of these auxiliary checkers, said checker being indicated by the

numeral 22. Said checker, it will be noted, is half of a standard checker, the standard checker 15 being divided along a plane symmetrically disposed with respect to the groove 21. In other words, the checker shown in Figure 3 has a cross sectional contour bounded by the sides of half of a hexagon, the dividing line being parallel with one side of said hexagon and passing through the center of said hexagon.

Another supplementary checker contemplated by the present invention is illustrated in Figures 4 and 5 and is indicated by the numeral 23. Said checker 23 is similar in many respects to the standard checker 15, including height, but differs from the standard checker 15 in the respect that it embodies extra material and in the further particular that instead of being bounded by six sides lying in a hexagon it is bounded by a symmetrical five-sided figure or pentagon. Figure 4 shows in broken lines how a hexagon bounding a corresponding checker 15 would appear superimposed upon the supplementary checker 23. Said checker 23 includes four flat faces 16 equal to the corresponding flat faces 16 of the checker 15. Said checker 23 includes the broad flat face 24, the plane of which is disposed in symmetrical relationship with the flat faces 16-16.

The four flat faces 16 of the pentagon 23 are joined by the three arcuate surfaces 26-26. The fifth face 24 of the pentagon 23 is narrower than the distance between opposite faces 16-16 of said pentagon or of the corresponding hexagon. In forming the face 24 the arcs 25-25 contiguous to the adjacent opposite faces 16-16 are continued downwardly in directions parallel with the axis of symmetry 26 of the pentagon 23. In other words, the arcuate surfaces 25-25 have tangential surfaces 27-27 extending therefrom parallel to the axis of symmetry of the pentagon 23, which tangential surfaces terminate in the surface 24 which lies at right angles to the axis of symmetry of the pentagon 23.

It will be noted that the surface 24 is located appreciably nearer to the axis of the center hole 17 than is the sixth vertex of the corresponding hexagon, all of which is clearly shown in Figure 4.

The supplementary checker 23 has the seven holes 17, 18 corresponding to those in the standard checker 15. The checker 23 is provided at the top thereof with the transversely extending groove 28 communicating with the center hole 17, through the recess 19, with the holes 18-18, and with one arcuate surface 26 and the opposite arcuate surface 25.

The half checkers 22 and the pentagon checkers 23, as noted above, are supplementary checkers and for convenience may be referred to as edge checkers. Said edge checkers 22 and 23 are, according to the present invention, mounted in assembled relationship with the standard checkers 15 to provide the flat surfaces bounding the checker body within the ring wall 10. Considering any horizontal plane throughout the height of the checker assembly within the ring wall 10, the perimeter of the plane figure denoting the cross section at that particular height is bounded by chords, the chords which bound the half checkers interspersed with regular checkers being indicated by the numerals 28-28 and the chords bounding the pentagon checkers being indicated by the numerals 29-29.

With the outer surface of the checker body bounded by flat surfaces it is a relatively simple matter to build up the ring wall 10 to engage said

flat surfaces. The amount of cutting of bricks in the ring wall 10 is minimized, and an intimate relationship is obtained between the ring wall and the checker body. This contributes to the stability of the checker body and also permits the removal of any portion of the checkers without disturbing the ring wall. Replacement checkers can be inserted with ease.

The exterior surface of the ring wall 10 may present a rather irregular contour. This is of small consequence because a substantial space between the inside of the shell 14 and the exterior of the ring wall 10 is normally provided to permit expansion of the stove with respect to the stove shell 13, and also to permit the insertion of insulating material, which is merely of filler character and which need have no bond with the ring wall. For this reason the bricks on the exterior of the ring wall 10 may present a somewhat irregular surface and the cutting, if any, need not be exact.

The present invention has the advantage that a checker body may be built up having plane surfaces around its perimeter using only standard hexagonal checkers, half checkers, and pentagonal checkers.

Though a preferred embodiment of the present invention has been described in detail, many modifications will occur to those skilled in the art. It is intended to cover all such modifications that fall within the scope of the appended claim.

What is claimed is:

In combination, in an assembly of checkers, regular checkers each having a cross sectional contour in the form of a regular hexagon, supplementary checkers each comprising half of a regular checker divided along a plane extending through opposite vertices of said regular hexagon and other supplementary checkers each having a cross sectional contour in the form of a pentagon symmetrical about an axis, four sides of said pentagon lying in colinear relationship with the sides of said regular hexagon, two opposite sides of said pentagon being parallel with said axis of symmetry and connected to the fifth side through

arcs connecting with lines parallel with said axis of symmetry of said pentagon, terminating at said fifth side to form an extension of less width than the width between said opposite sides, said fifth side being closer to the center of the corresponding hexagon than a vertex thereof, each of said checkers of pentagonal contour being provided with a plurality of holes extending therethrough, all sides of said pentagon being located outside of said holes, whereby each of said pentagonal checkers includes a continuous outer wall braced by partitions between said holes, said regular checkers and said first mentioned supplementary checkers being arranged in alternate side by side relationship with one another forming a group, the non-hexagonal sides of said group of said first mentioned supplementary checkers being disposed in coplanar relationship with sides of said regular checkers forming an extended flat surface along the exterior wall of said assembly, said second mentioned supplementary checkers of another group being disposed with their said opposite sides in side by side relationship, with the fifth sides thereof disposed in coplanar relationship forming a second extended flat surface of said assembly, an end checker of the first group and an end checker of the other group being disposed in side by side relationship, forming a corner construction with the extended flat surfaces angularly disposed.
